UNITED STATES PATENT OFFICE.

GARDINER INGLIS, OF AIRDRIE, SCOTLAND.

FIRE-TUBE STEAM-BOILER.

SPECIFICATION forming part of Letters Patent No. 767,816, dated August 16, 1904.

Application filed February 17, 1904. Serial No. 193,980. (No model.)

To all whom it may concern:

Be it known that I, GARDINER INGLIS, engineer, a subject of the King of Great Britain and Ireland, and a resident of Airdrie, county of 5 Lanark, Scotland, have invented certain new and useful Improvements in Fire-Tube Steam-Boilers of the Marine and Like Type, of which the following is a specification, and for which a patent has been applied for in Great Britain, 10 No. 5,939, dated the 14th day of March, 1903, and in Germany, No. I. 7,332, dated the 1st of May, 1903.

This invention has reference to improvements in fire-tube steam-boilers of the marine and like type, and is particularly suitable where forced or induced draft is used, and has essentially for its objects to give the following advantages: first, improved combustion of furnace-gases and fuel; second, delivery of the gases from the furnaces to the fire-tubes of boiler at a uniform temperature; third, when working with forced or induced draft to prevent the gases when they reach the tubes of being at such a temperature as 25 would injure or cause damage to the tube ends; fourth, to prevent clinker or other partially-burned fuel from being forced into the tubes and onto the tube-plate in such a manner as would cause serious obstruction; fifth, 30 to prevent cold air from reaching the tube-plate when the furnace-doors are open while charging the furnaces with fuel, and, sixth, to reduce the terminal temperature of the gases as they come to the uptake.

35 My improvements essentially consist in combining with the ordinary forward or primary furnace-flues and back combustion-chamber of boiler a return or secondary combustion-flue or wide chamber, so that the gaseous products of combustion shall be brought to a further chamber located at the front end of boiler and then pass through the fire-tubes to the uptake, the fire-tubes being secured at their ends to and carried by the front and 45 back end plates of boiler.

In order that my said invention and the manner of carrying same into practice may be properly understood, I have hereunto appended three sheets of explanatory drawings, in 50 which—

Figure 1 is a longitudinal vertical section of a steam-boiler of the marine type, showing the application of my improvements thereto, while Figs. 2 and 3 are end views corresponding to Fig. 1 and as taken near the front and 55 rear ends, respectively, of boiler.

Referring to the drawings, within the shell A of the steam-boiler there would be fitted at its lower part any desired number of corrugated or other flues B, carrying the fire-grates 60 C. The usual combustion-chamber D would be fitted at the rear part of boiler.

By my improvements I lead a large flue or wide chamber E from the upper part of the combustion-chamber D to the front end of 65 shell A of boiler and communicating with a chamber or casing F, located at the front of boiler. This casing F would preferably be lined with fire-brick F', but may have instead a water-jacket chamber and be fitted with any 70 ordinary-formed door or doors. The fire-tubes G would extend from this chamber F to the uptake H and be secured at their ends to the front and back end plates A' A², respectively, of shell A of boiler.

75 By this improved construction of steam-boiler the gases from the furnaces C would pass through the primary flues B in what may be termed the "lower" zone of the boiler into the combustion-chamber D, from whence the 80 combined gases would pass through the secondary combustion flue or chamber E to the front chamber F and from thence through the fire-tubes G to the uptake H in what may be termed the "second" zone of the furnace, 85 while the upper steam-space of the boiler provided with the stay-rods I may be termed the "upper" zone.

I claim as my invention—

1. A steam-boiler comprising a shell, end 90 plates therefor, a flue open at one end, a combustion-chamber at right angles thereto, both secured in an end plate, a second single flue of large cross-section substantially parallel with the first flue, a casing at one end of the boiler 95 into which said second flue opens, a number of fire-tubes secured in the end plates and open at one end to said casing.

2. A steam-boiler, comprising a shell, end 100 plates therefor, a flue open at one end, an up-

right combustion-chamber within the shell, a second single flue of large cross-section, parallel with the first, a casing at one end of the boiler to which said flue opens, a number of 5 fire-tubes secured in the end plates and open to said casing.

3. A steam-boiler comprising a shell, end plates therefor, a flue for the fire, a substantially parallel second flue, both secured at adjacent ends in one end plate, a combustion-chamber connecting their other ends, a number of fire-tubes secured in the end plates adjacent to and surrounding a portion of said second flue, and a casing connecting said tubes and said second flue substantially as described. 10

4. A steam-boiler, comprising a shell, end plates therefor, a flue for the fire, a substantially parallel second flue, both secured at adjacent ends in one end plate, a combustion-chamber connecting their other ends, and entirely within the shell, a number of fire-tubes 20 secured in the end plates adjacent to and surrounding a portion of said second flue, and a casing connecting said tubes and said second flue, substantially as described. 25

5. A steam-boiler, comprising a shell, end plates therefor, a plurality of flues secured in one end plate, a flue E parallel thereto and also secured in said end plate, a combustion-chamber connecting their other ends, a number of fire-tubes secured in the end plates, and a casing connecting the flue E and fire-tubes. 30

6. A steam-boiler, comprising a shell, end plates therefor, a plurality of flues secured in one end plate, a flue E parallel thereto and also secured in said end plate, a combustion-chamber entirely within said shell, connecting their other ends, a number of fire-tubes secured in the end plates, and a casing connecting the 40 flue E and fire-tubes.

7. A steam-boiler, having a cylindrical shell, end plates therefor, said boiler having three zones, as follows: a lower zone and a flue therein secured at one end in an end plate, a second 45 zone and a flue E and a number of fire-tubes therein, the flue secured in one end plate and the tubes in both end plates, and a third zone comprising the steam-space, a casing connecting the flue E and tubes and a combustion-chamber connecting the flue of the lower zone 50 with the flue E. 55

8. A steam-boiler, having a cylindrical shell, end plates therefor, said boiler having three zones as follows: a lower zone and a number 55 of flues therein, a second zone, a flue E and a number of fire-tubes therein, the tubes secured

in both end plates, the flue secured in the same end plate, a combustion-chamber connecting the flues, and a casing connecting the flue E and tubes, and a third zone comprising the 60 steam-space.

9. A steam-boiler, having a cylindrical shell, end plates therefor, said boiler having three zones, as follows: a lower zone and a flue therein secured at one end in an end plate, a second 65 zone and a flue E and a number of fire-tubes therein, the flue secured in one end plate and the tubes in both end plates, and a third zone comprising the steam-space, a casing outside the shell connecting the flue E and tubes and 70 a combustion-chamber entirely within the shell connecting the flue of the lower zone with the flue E. 75

10. A steam-boiler, having a cylindrical shell, end plates therefor, said boiler having three zones as follows: a lower zone and a number of flues therein, a second zone, a flue E and a number of fire-tubes therein, the tubes secured in both end plates, the flues secured in the same end plate, a combustion-chamber entirely within the shell, connecting the flues, and a casing outside the shell connecting the flue E and tubes, and a third zone comprising the steam-space. 80

11. A steam-boiler, comprising a cylindrical shell, end plates therefor, three fire-flues secured at one end in one of said plates, a flue E of larger diameter above the fire-flues, secured in the same plate, a combustion-chamber connecting their other ends, a number of 90 fire-tubes clustered about the flue E and secured at each end in one of the end plates, and a casing connecting the flue E and tubes substantially as described. 95

12. A steam-boiler, comprising a cylindrical shell, end plates therefor, three fire-flues secured at one end in one of said plates, a flue E of larger diameter above the fire-flues secured in the same plate, a combustion-chamber entirely within the shell connecting their other ends, a number of fire-tubes clustered about the flue E and secured at each end in one of the end plates and a casing outside the shell connecting the flue E and tubes, substantially as described. 100 105

In testimony whereof I have signed my name to this specification in the presence of two subscribing witnesses.

GARDINER INGLIS.
